SEWING KIT

Filed April 9, 1929

UNITED STATES PATENT OFFICE

JOSEPH F. KLATT, OF PORTLAND, OREGON

SEWING KIT

Application filed April 9, 1929. Serial No. 353,731.

This invention relates to a sewing kit and pertains particularly to a kit designed for carrying spools of thread, needles, pins and a thimble, and having means associated therewith whereby the threading operation of a needle may be expedited.

The primary object of the present invention is to provide a kit of the above described character having means for supporting a number of spools and controlling the withdrawal of the cotton therefrom so that after a desired amount of cotton or thread has been removed the remaining portion will be held in an easily accessible position.

Another object of the invention is to provide, in a sewing kit, a spool holding unit having an improved thread guiding means associated therewith.

20 A still further object of the invention is to provide a sewing kit in which may be kept all of the articles necessary for a sewing operation and which will be of compact design.

25 The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from 30 the salient features of the invention as expressed in the appended claims.

In the drawing:—

Figure 1 shows the kit embodying the present invention;

40 Figure 2 shows a central longitudinal sectional view through the structure shown in Figure 1, the section being taken substantially upon the line 2—2 thereof;

45 Figure 3 is a transverse sectional view;

Figure 4 is a detailed view of the thread holding unit showing the same in side elevation;

50 Figure 5 is a detailed sectional view of a portion of the thread holding unit, showing

the method of guiding the thread through the wall thereof;

Figure 6 is a detail view in side elevation of a guide eye for one of the spools of thread in the holding unit.

55

Referring to the drawing in detail, where-in like numerals of reference indicate corresponding parts throughout the several views, the numeral 1 indicates the body or casing of the kit embodying the present invention, the same being transversely divided, as shown, to form the upper and lower sections 2 and 3. The upper section is provided with a bottom 4 and has threadably secured thereon a cap 5 upon the top of 60 which is formed a hollow wall structure 6 open at each end and packed with a soft material such as cotton or hair, as indicated by the numeral 7. This packing material 7 is provided for the reception of needles or 65 pins which the user of the kit desires to keep at hand while working.

70 The central portion of the top adjacent this wall 6 is provided with a closed casing 8 having a top wall thereof provided with a pair of 75 apertures 9 and having positioned therein a sponge 10, portions of which are exposed through the apertures 9, as shown.

At the opposite side of the casing 8, a post 11 is mounted and formed transversely of 80 this post in a line at right angles to the adjacent face of the wall 6 is a passage 12, the outer end of which opens into a groove 13 formed transversely of the post. Formed through the wall 6 in alinement with the 85 passage 12 of the post 11, is an opening 14. The passage 12 is designed to receive a needle for a threading operation, the needle being inserted from the outer end of the passage and extended therethrough until the eye 90 thereof is positioned in the groove 13, when in this position the pointed end of the needle will be extended through the opening 14 in the wall face and held in the packing 7 thereof. Moisture may be obtained from the 95 moistened sponge 10 with which to moisten the end of a thread so that the same may be pointed for assisting the threading operation.

The top of the post 11 is provided with a pair of crossed notches or grooves 15, the end 100

edges of which are sharpened so that a thread may be conveniently cut therein.

The interior of the upper portion 2 of the kit is provided with an annular body of soft material as indicated at 16 and in the central portion of this body in the opening 17, there is positioned a pair of resilient portions 18 secured to the bottom 4, as shown, to receive and carry a thimble 19.

10 The portions 2 and 3 of the kit are secured together by a hinge member 20 and diametrically opposite the hinge is placed a securing member comprising a hasp 21 hingedly secured to the upper portion 2 of the kit and 15 slotted to receive a rotatable button 22 carried upon the lower portion of the kit.

In the lower portion 3 of the kit there is placed a cylinder 23 having a bottom 24 and having extending upwardly centrally there- 20 through from the bottom, a post 25.

The bottom of the cylinder 23 rests upon a spring 26 carried within the cap 27 which threadably engages over and closes the lower end of the portion 3 of the kit, as shown.

25 The upper end of the post 25 extends through an aperture in a centering bar 28 which extends transversely of the top of the kit portion 3 in the manner shown in Figure 3.

As is shown in Figure 2 the cylinder 23 has 30 surrounding it an outer wall 29 which is also carried upon the bottom 24 and between the outer wall 29 and the wall of the cylinder proper a suitable packing 30 is placed to receive needles stored in the kit.

35 The post 25 is designed to extend through and hold in position in the cylinder, one or two spools of thread, there being shown in connection with this description two spools 31 and 32 separated by an elongated plate 33 which carries at one end a vertical pin 34 terminating at its lower end in an opened loop or eye 35. The eye 35 is designed to receive the thread from the lower spool 32 to guide the same from the spool at right angles to the 45 body thereof and this thread is passed up over the cylinder and through an eye 36 formed at the upper end of a vertical arm 37 carried by and projecting upwardly from the wall of the cylinder in the manner shown.

50 In the upper portion of the cylinder adjacent the upper spool 31 a slot 38 is formed and secured to the outer face of the cylinder wall adjacent the slot 38 is an arm 39 which terminates in an open eye 40 at the lower end 55 of the slot, the slot and eye being formed to receive the thread from the upper spool 31 to guide the same from the spool substantially at right angles to the longitudinal axis thereof so that a smooth unwinding of the thread 60 will result. The thread taken from the upper spool and passed through the eye 40 is then extended upwardly upon the outer side of the spool cylinder to an open eye 41 formed at the upper end of an upright arm 42 like 65 and carried upon the upper edge of this cylin-

der in the same manner as the arm 37. The arms 37 and 42 are in spaced parallel relation and the eyes 36 and 41 are arranged in substantially the same plane and are in a plane below the upper end of the spool carrying post 25 as shown in Figures 2 and 4. When the spool carrying cylinder is in place with the post 25 extending upwardly through the cross bar 28 and the receptacle closed, the eyes 36 and 41 will be slightly below the top edge of the portion 3 of the kit and this top edge is provided adjacent each eye with a transverse groove 43 through which the thread of the adjacent eye may be passed. When the thread carrying cylinder is in place the arms 37 and 42 are positioned upon opposite sides of the bar 28 so that the bar will act to prevent the turning of the cylinder 23 and will also guide the cylinder when the latch connecting the kit portions is released and the kit opened and the spool carrying cylinder forced upwardly in the lower portion thereof by the spring 26.

It will be readily seen that when the kit is opened the spring 26 will raise the spool carrying cylinder bringing the top thereof into substantially the same plane as the top edge of the encasing kit portion and exposing to view the needles positioned around the cylinder in the material 30.

Upon the outer face of the lower portion of the cylinder wall adjacent each of the grooves 43, there is secured a resilient arm 44 which extends over the adjacent groove 43 and is free from contact with the kit body at the end adjacent the latching button 22. When the threads are drawn from the holder they are slipped under these resilient arms and held thereby until tension is placed upon them to draw the thread out of the cylinder as needed.

The under face of the bottom 4 of the upper portion 2 of the kit is centrally depressed as indicated at 45 to receive the upper end of the post 25 when the kit portions 2 and 3 are brought into superposed relation so that the post will be properly centered and no binding of the thread spool carrying cylinder with the wall of the kit will take place, as the cylinder is forced downwardly therein against the tension of the spring 26.

From the foregoing description it will be readily seen that with a kit of the character herein described all of the articles necessary for a sewing operation may be kept conveniently at hand and in addition to this the usual difficult operation of threading a needle will be eliminated by the use of the members 6 and 11.

The device is particularly well adapted for use by travelers where such things are frequently required and where articles taking up a minimum of space are desirable.

Having thus described my invention, what I claim is:—

1. In a sewing kit of the character de- 130

scribed, a tubular casing formed in an upper and lower section, hinged means connecting said sections, a removable cap closing the lower end of the lower section, a spool carrying cylinder designed to be positioned in the lower section, a pin extending longitudinally through said cylinder, a resilient element between said cylinder and said cap, said upper section normally bearing down upon said pin and maintaining said resilient element under tension, guide means for conducting a thread from a spool traversed by said pin to the exterior of the casing, and a guide element for the upper portion of said pin.

15 2. In a sewing kit of the character described, a tubular casing formed in an upper and lower section, hinged means connecting said sections, a removable cap closing the lower end of the lower section, a spool carrying cylinder designed to be positioned in the lower section, a pin extending longitudinally through said cylinder, a resilient element between said cylinder and said cap, said upper section normally bearing down upon said pin and maintaining said resilient element under tension, guide means for conducting a thread from a spool traversed by said pin to the exterior of the casing, a guide element for the upper portion of said pin, and resilient means 25 carried by and exteriorly of the lower portion of the casing for securing the outer end of a thread leading from the casing.

3. In a sewing kit of the character described, a casing, a thread spool cylinder removably positioned in the casing, a guide post within the cylinder for receiving spools, guide arms mounted upon the upper edge of said cylinder each terminating in a guide eye, means for leading a thread from each guide 35 eye to the exterior of the casing, and means arranged laterally of said guide post for guiding thread from spools thereon laterally from the body of the spool.

4. In a sewing kit of the character described, a casing, a thread spool cylinder removably positioned in the casing, a guide post within the cylinder for receiving spools, guide arms mounted upon the upper edge of said cylinder each terminating in a guide eye, spacing means designed to be interposed between a pair of spools traversed by said post and held in position by the post, a guide eye carried by said spacing means, and guide means carried by the wall of the cylinder for 45 leading thread from the other of the spools in a line substantially at right angles to the body of the spool.

In testimony whereof I hereunto affix my signature.

JOSEPH F. KLATT.
